UNITED STATES PATENT OFFICE.

GEORGE E. ECKLER, OF AKRON, OHIO.

COLLAPSIBLE CORE.

1,361,840.

Specification of Letters Patent. Patented Dec. 14, 1920.

Application filed October 18, 1919. Serial No. 331,552.

To all whom it may concern:

Be it known that I, GEORGE E. ECKLER, a citizen of the United States, residing at Akron, in the county of Summit and State 5 of Ohio, have invented new and useful Improvements in Collapsible Cores, of which the following is a specification.

This invention relates to improvements in cores for manufacturing the outer shoes 10 or casings for pneumatic tires, and has particular relation to that type of such cores which are made up of separable sections adapted to abut in the form of an annulus.

The primary object of the invention is to 15 provide a new and improved means for holding and locking the several sections of which the core is composed in assembled annular relation.

Another object is to provide a collapsible 20 core of the character described of simple construction which may be quickly assembled or collapsed and which when assembled will provide a firm annular mandrel for imparting to the interior of the tire shoe the 25 desired shape.

A still further object is to provide a collapsible core having a fastening means which 30 will hold the several parts of which it is composed in perfect alinement after long and continued use.

With the foregoing and other objects in view, the invention consists in the novel construction, combination and arrangement of parts hereinafter specifically described and 35 illustrated in the accompanying drawings which form a part hereof wherein is shown the preferred embodiment of the invention, but it is to be understood that changes, variations and modifications can be resorted to 40 which come within the scope of the matter hereinafter claimed.

In the drawings in which like numerals of reference are employed to indicate similar parts in the different figures:

Figure 1 is a side elevation of a core embodying this invention,

Fig. 2 is a side elevation of the locking ring employed in assembling the core.

Fig. 3 is a transverse cross-sectional view 50 of the assembled core taken approximately on line 3 of Fig. 1.

Fig. 4 is a similar cross-sectional view of one of the core sections.

Fig. 5 is a cross sectional view of the locking ring taken approximately on line 5 of Fig. 2.

A ring core embodying this invention con-

sists of a plurality of separable sections which when assembled together, as herein-after described, constitute an annular member, the peripheral and lateral faces of which are shaped to impart a preferred configuration to the corresponding inner face of the tire or tire shoe which is to be manufactured thereon. The sections which are employed 60 to form the annular core are designated in the drawings by the reference numerals 6, 7, 8 and 9 and are provided with inwardly extending flanges 10. These flanges are all similar and, in the embodiment of the invention shown in the drawings, are provided on one lateral face with the laterally projecting ribs or shoulders 11. The opposite face 12 of all the flanges 10 are provided with longitudinal grooves which, when the 75 several core sections are assembled, provides an annular groove or channel 13. The outer wall 14 of this annular channel 13 is preferably at right angles to the lateral face 12 of the flanges 10 and also at right angles 80 to the bottom face of the groove. The inner wall 15 of the channel 13 is disposed at an obtuse angle to the bottom face of the channel 13 so as to provide a seat for the face 19 of the annular rib 17 on the ring 16 as 85 hereinafter described.

The numeral 16 is used generally to designate a locking ring having a base portion 18 which is parallelly disposed to the axis of the ring and is adapted to support the core 90 sections 6, 7, 8 and 9 and to hold the said sections from inward movement. Extending outwardly from one lateral edge of the base portion 18 and at a right angle thereto is a circumferentially extending flange 21 which 95 is provided with a laterally extending circumferential rib 17 having an inclined face 19 which is adapted to seat against the face 15 of the channel 13. When the core is assembled, the lateral side 21 of the ring 16 100 is in contact with the core section, only along the face 19 of the rib 17. The locking ring 16 is provided with lateral extending bolt receiving apertures 23 at points coinciding with the abutting faces of the several core 105 sections; each core section being provided on the ends of its flanges 10 with a laterally extending semi-circular groove which forms when the core is assembled, a laterally extending bolt receiving aperture which coincides with the apertures 23 in the ring 16.

In use the core sections, 6, 7, 8 and 9 are assembled with the inwardly extending flange 10 of each section in contact with the

base 18 of the flange 16, the bolts 24 are then positioned through the apertures 23 of the ring 16 and through the semi-circular channel positioned as aforesaid in the ends 5 of the flanges 10, the nut 25 is then screwed home on the bolt 24 forcing the inward face 15 of the groove 13 against the inward face of the flange 19. As the nut 25 is tightened, the various core sections are 10 pressed inwardly against the base portion 18 of the ring 16 and are held from inward movement by said base portion. It will be noted that in the assembled core the ribs 17 do not fill the groove 13 and that the out- 15 wardly extending flange 21 does not contact with the lateral side of the core flanges 10 except along the face 15. The only part of wear being along the contacting surfaces 15 and 19, as these surfaces wear with use 20 the ribs 17 will extend farther in the groove 13 and will effectually hold the sections securely in abutment.

Having thus described my invention what I claim as new and desire to secure by Letters-Patent is:—

1. A collapsible core of the character described comprising a plurality of separable sections adapted to abut in the form of an annulus, said annulus having an inwardly directed flange, an annular channel in one lateral face of said flange, the bottom face of the channel being on a line parallel with the lateral face of the flange, the inner wall of the channel being inclined at an obtuse angle to the bottom thereof and a ring having a base portion parallel to its axis and a side portion extending outwardly from one lateral edge of said ring, a laterally directed, circumferentially extending flange portion 30 positioned on one lateral side of said side portion, the inner face of said flange being inclined toward the base of the ring so as to register with the inner wall of said channel, bolt receiving apertures in said flange, corresponding apertures in the side wall of said ring, bolts adapted to be secured in said apertures so as to force the inner face of said flange laterally against the inner wall of said channel and hold said sections in 35 assembled relation.
2. A collapsible core of the character described comprising a plurality of separable sections, adapted to abut to form an annulus, each of said sections having an inwardly projecting portion which forms when the core is assembled an annular flange, each end of each section being provided with laterally directed semi-circular grooves adapted to form in coöperation with 40 the abutting section bolt receiving apertures, an L-shaped ring having positioned in its lateral sides a plurality of bolt receiving apertures positioned in said ring at a point coinciding with the bolt receiving apertures 45 in said flange, a bolt adapted to be posi-

tioned through the aperture in said ring and said flanges and fastened by means of a nut operated on said bolt so as to secure the said sections in abutment against the base of said ring.

70

3. A collapsible core of the character described comprising a plurality of separable sections adapted to abut in the form of an annulus, said annulus having an inwardly directed flange, an annular channel in one lateral face of said flange, the bottom face of the channel being on a line parallel with the lateral face of the flange, the inner face of the channel being inclined at an obtuse angle to the bottom thereof and a ring having a base portion parallel to its axis and a side portion extending outwardly from one edge of the ring, a laterally, directed circumferentially extending flange positioned on one lateral side of said side portion, the inner face of said flange being inclined toward the base of the ring so as to register with the inner face of said channel, a semi-circular, laterally directed groove in the abutting flange faces of each section which provides in coöperation with the abutting section, a bolt receiving aperture in the assembled core, a plurality of bolt receiving apertures in the side portion of said ring, said inner face of said flange being held against the inner face of said channel by means of a bolt positioned in said aperture and retained therein by a nut substantially as described.

4. A core of the class described comprising an annulus having an inwardly directed flange, said annulus composed of separable sections held in abutment by a ring to which said sections are secured by means of bolts running laterally through said ring and between the abutting ends of the sections, the abutting faces of each flange having a laterally extending groove adapted to register with a similar groove in the abutting section to form an aperture to receive said bolt.

100

5. A core of the class described, comprising an annulus having an inwardly directed flange, said annulus composed of separable sections held in abutment by an L-shaped ring to which said sections are secured by means of bolts running laterally through the side portion of said ring and between the abutting ends of the flanges on said sections which are grooved to receive said bolts, a circumferentially extending channel in one lateral face of said flange the inner side of said channel inclined inwardly, a circumferentially extending laterally directed rib on the said side portion of said ring, the inner face of which is inclined outwardly and is adapted to seat on the inner face of said groove.

110

In testimony whereof I have hereunto set my hand.

GEORGE E. ECKLER.
